UNITED STATES PATENT OFFICE

OTTO V. THIELE, OF RIDGEWOOD, NEW JERSEY, ASSIGNOR TO THE SUPERHEATER COMPANY, OF NEW YORK, N. Y.

SUPERHEATER HEADER

Application filed August 1, 1928. Serial No. 296,703.

This invention relates to locomotive superheaters of the type in which the superheating elements are tubular in form and are located in the flues or fire tubes of the boiler with their ends connected to a header located in the smoke-box, the steam being led from the boiler to the header, circulating from the header through the heating units or elements, and being returned by them to the header, 10 and then being delivered by the header in superheated state to the engine.

The general arrangement of this type of superheater has become thoroughly standardized throughout the world. The header is 15 universally located in the upper portion of the smoke-box between the front flue sheet and the smoke-stack. The material used during the last twelve or fifteen years for these headers has been practically universally cast 20 iron and this has in practice proved entirely satisfactory. There are some advantages, however, in using steel instead of cast iron, the principal one being that the header can thereby be made materially lighter in weight, 25 which is sometimes a consideration. This has been recognized, and constructions employing steel have been proposed heretofore. Casting the header of steel has proved rather difficult so far, and suggestions for the use 30 of steel have been pretty well limited to steel in the form of rolled sheets. These sheets can be shaped and welded into headers in various ways. It is highly desirable, however, for the sake of interchangeability to have the 35 steel headers of such conformation that heating elements designed for use with the standard cast iron headers can be equally well used in connection with the substituted steel headers and vice versa. With this necessity 40 fronting the engineer, a number of difficulties appear.

It is the purpose of the present invention to furnish a header which shall meet the requirements just pointed out. The detailed 45 advantages of the construction forming the basis of the present invention will be apparent from the following specification.

The invention is illustrated in the drawings herewith, in which Fig. 1 is a plan view, 50 partly in section on line 1—1 of Fig. 2, of a

header according to the present invention; Fig. 2 is a front view of the header, a portion of it being in section on the line 2—2 of Fig. 1; Fig. 3 is a sectional view on line 3—3 of Fig. 1; Fig. 4 is a view similar to Fig. 3 of the modification; Figs. 5 and 6 show in plan two elements which are united to form a partition used in the construction; Fig. 7 shows the two elements secured together in their relative position ready for use in a header; 55 Figs. 8 and 9 are lateral views of Figs. 5 and 6 respectively; Figs. 10 and 11 show two sheets used in the construction as they appear before they are bent into shape; Figs. 12 and 13 are lateral views of the same two 60 sheets; Figs. 14 and 15 show the two sheets bent into shape ready for assembly, these two views being lateral views, and Figs. 16 and 17 show two ways in which certain portions of the plates shown in Figs. 10 and 11 65 are reinforced.

The first four figures are on a larger scale than Figs. 5—15, and Figs. 16 and 17 are on a still larger scale.

In making a header according to my invention, I first cut two sheets into the shape illustrated in Figs. 10 and 11. Each sheet has a central portion 1^a and 1^b respectively and a number of tabs 2^a—2^a and 2^b—2^b respectively, projecting from them. For reasons which will appear more clearly hereinafter, one set of tabs (the lower in Figs. 10 and 12 and the upper in Figs. 11 and 13) are made heavier. This can be done in any preferred manner. Special sheets, for example, can be rolled for this purpose. In Figs. 16 and 17 there are illustrated two ways in which this reinforcing can be accomplished with the use of ordinary sheets. Referring for example to Fig. 16, a portion 3 75 of the sheet 1 is bent over into contact with the sheet. Holes 4—4 have been formed by punching or otherwise in the portion 3 and the portion 3 is welded to the sheet 1 by filling the welding material into the holes 4. 80 These holes are distributed over available areas throughout the portions 3. The welding is preferably done by oxy-acetylene 85 means.

Instead of punching the plate 3 and using 90

the oxy-acetylene method, an electric resistance method can be used as illustrated in Fig. 17 where the bent-over portion 3 is welded to the sheet 1 at the points 4^a—4^a.

5 Holes 15—15 are formed by drilling or any preferred manner in the reinforced tabs 2^a—2^a and 2^b—2^b. These holes are reamed out so that they have conical seats as clearly illustrated in Figs. 2 and 3.

10 After the sheets have been finished as illustrated in Figs. 10 to 13, they are next bent into the shape illustrated in Figs. 14 and 15. The tabs 2^a—2^a at one side of the sheet will lie above the corresponding tabs 2^a—2^a at the 15 other side and similarly tabs 2^b—2^b lie one set opposite the other. The portion between the tabs of each sheet forms an elongated chamber open at the side toward the tabs as well as at its ends.

20 In Figs. 5 to 9 is illustrated a partition which is to be used in connection with the portions of Figs. 14 and 15 in making the header. This partition comprises two strips of a width equal to the distance between the 25 tabs 2^a—2^a and 2^b—2^b in Figs. 14 and 15. The strip in Fig. 5 is bent so that it has certain straight portions 6^a—6^a in a straight line, and projecting from these alined portions it has rectangular boxes or fingers 7^a. The distance between the adjacent fingers 30 7^a—7^a is wider than the width of the fingers.

The second sheet, shown in Fig. 6, is symmetrical with respect to that of Fig. 5. Straight portions 6^b—6^b have extending from 35 them the fingers 7^b—7^b which are also spaced farther apart than their own width.

The outer portions 8^a—8^a and 8^b—8^b extend beyond the alined portions 6^a and 6^b, and these extended parts are round in shape 40 as shown at 9^a and 9^b of Figs. 8 and 9 respectively.

45 These two bent strips of Figs. 5 to 9 are next assembled into the position shown in Fig. 7. The fingers of each strip extend into the spaces between the fingers of the other, and the tips of the fingers of one contact with the straight portions of the other. At these points of contact 10—10 the two strips are preferably secured together. This may be 50 done either by riveting as illustrated in Fig. 7, or by any other preferred means.

55 As clearly appears in Fig. 7, this procedure leaves slots 11—11 between adjacent fingers, the purpose of which slots will appear presently.

This partition of Fig. 7 is next inserted 60 into one of the bent sheets of Figs. 14 and 15 in a manner that will appear more clearly from an inspection of Figs. 1, 2 and 3. The edges of the tabs 2^a—2^a contact with the edges of the fingers 7^a—7^a and of the straight portions 6^a—6^a, while the edges of the tabs 2^b—2^b contact with the edges of the fingers 7^b—7^b and of the straight pieces 6^b—6^b. In other 65 words, the two plates of Figs. 10 and 11 are

so placed relatively to each other that their tabs occur in alternating relation in two parallel planes and the double partition of Fig. 7 is inserted between the two, its edges abutting against the edges of the former. The 70 edges are next welded together, the edges of one strip being welded to one plate and its tabs and the edges of the other strip to the other plate and its tabs. It will be noted that every portion along which welding has to be done is perfectly accessible from the outside. Preferably reinforcing corner pieces 1^e and 1^f are secured by welding in the positions 75 shown in Fig. 1.

In assembling the strips and plates as just described, the portions 9^a—9^a and 9^b—9^b come to lie respectively in the correspondingly shaped ends of the elongated chamber shown in end view in Figs. 14 and 15. These arcuate edges are likewise welded together. The 80 result of these manipulations is a structure in which there are two entirely closed chambers not directly communicating with each other, and having intermeshing fingers, these 85 fingers being separated by slots.

The holes 15—15 described above will all lie in one face and their spacing has been made such in the first place that in the assembled structure their arrangement is exactly the standard one corresponding to the 90 particular size and type of header. It will at once be understood by those skilled in this art that to these openings are secured the ends 16—16 of the tubular super-heater-elements. The ordinary way of securing 95 these ends to the header is illustrated for one pair in Fig. 2. Here it will be noted that the bolt 17 extends through the slot 11. Its head bears against the upper side of the header or more specifically against the upper end of the two strips forming the space 100 11. The lower end of the bolt 17 carries a nut which on being drawn up forces the clamp 18 upward, pressing against the two washers 20—20, thereby forcing the enlarged 105 ends 21—21 of the superheater elements against their seats. This is in accordance with the ordinary construction. As many 110 bolts will extend through each slot 11 as there are pairs of element ends.

115 The reason for thickening those portions of the plates to which the ends of the super-heating elements are secured is two-fold. The deforming tendency of the pressure exerted by pulling up the nuts on bolts 17 is thereby better resisted, and more material is present for the formation of seats for the enlarged unit ends. The latter becomes important as the seats are re-ground from time to time.

120 In order to admit steam into this header, a portion is cut out of one of the elongated chambers along the line 22, and into the opening so formed is welded the connection 125 23 to which the end of the dry pipe is se-

cured. In a similar fashion, portions are cut out from the elongated chamber of the other plate along the lines 24—24, and connections 25—25 are welded into these openings. The holes may be cut out before the sheets are bent, or at a subsequent stage. In the latter case the preferred method is by means of an oxy-acetylene flame.

Preferably the reinforced tabs 2^a and 2^b which will in the finished article lie on the outer sides extend beyond the edge of the sheet as shown at 26 and 27 in Figs. 10 and 11. These projecting portions will form supports for the header by means of which it can easily be secured in position in the smoke-box.

In the form of the header so far described, the elongated chambers are shown circular in cross-section. If preferred these chambers can be given a rectangular form as in 1^c and 1^d in Fig. 4. Except for this change in the shape of these elongated chambers, the header of Fig. 4 is closely similar to that of the form first described.

Other variations will readily occur in practice without a sacrifice of the real invention.

I claim:

1. The method of making a sheet-steel superheater header, including the steps of cutting a sheet to a generally rectangular form having rectangular spaced tabs on two opposite edges, the tabs on one edge lying opposite those on the other; bending the sheet so that the tabs of one edge lie above those of the other and are spaced from them, and so that the portion of the sheet between the tabs forms an elongated chamber closed on three sides.

2. The method of making a sheet-steel superheater header including the steps of cutting and bending a sheet in accordance with claim 1, bending a strip of sheet-steel of the proper width into such shape that it can be placed with its two long edges coinciding with the edges of the tabs and the edges of the sheet between the tabs, placing the strip into said position, and welding said edges together, thereby closing the fourth side of said chamber.

3. The method of making a sheet-steel superheater header, comprising the steps of cutting and bending two sheets in accordance with claim 1, placing them together so that the tabs of the two sheets lie in alternating relation in two planes, inserting a suitably formed partition in contact with all of the edges of all of said tabs, and with the edges of the sheet between the tabs, and welding it to said edges.

4. The method of making a partition for a sheet-steel superheater header, including the steps of cutting two strips of steel of the required length, bending each of them so it has portions lying in a line and fingers pro-

jecting from said line spaced farther apart than the width of the fingers, nesting the two strips so their fingers extend mutually into said wider spaces, the ends of the fingers contacting with said portions lying in a line, the sides of the fingers of one strip being spaced from those of the fingers of the other, and securing together said contacting portions.

5. The method of making a sheet-steel super-heater header, comprising the steps of cutting and bending two sheets in accordance with claim 1, placing them together so that their tabs lie in alternate relation in two planes, forming a double-walled partition by bending two strips of sheet steel of the proper width and length into such shape that they each have portions lying in a line and fingers projecting from said line spaced farther apart than the width of the fingers, nesting the two strips so their fingers extend mutually into said wider spaces, the ends of the fingers contacting with said portions lying in a line, the sides of the fingers of one strip being spaced from those of the fingers of the other, and securing said contacting portions together, inserting said partition in contact with all of the edges of all of the tabs and with the edges of the sheet between the tabs and welding it to said edges.

6. A sheet-steel superheater header including a steel sheet having a portion bent to form three sides of an elongated chamber, and having spaced tabs extending from the two long free edges, the tabs extending from one edge being alined with those extending from the other.

7. In a sheet-steel superheater header, the combination of a steel sheet having a portion bent to form three sides of an elongated chamber and having spaced tabs extending from the two long free edges, the tabs extending from one edge being alined with those extending from the other, and a steel strip bent to follow the edges of the tabs and the edges of the sheets between the tabs and secured to said edges.

8. In a sheet-steel superheater header, the combination of two structures in accordance with claim 7, each having an elongated chamber with parallel spaced fingers extending from and communicating with it, the fingers of one being inserted between the fingers of the other and the portions of each strip at the tips of the fingers being secured to the portions of the other strip between the fingers.

9. A structure in accordance with claim 6, one set of tabs being thicker than the other.

10. A structure in accordance with claim 6, the tabs of one set being made of two thicknesses of the sheet secured together.

OTTO V. THIELE.
